UNITED STATES PATENT OFFICE.

EDWARD A. LUZENBERG, OF SAN ANTONIO, TEXAS.

STAND FOR ROLLED GOODS.

1,390,299.

Specification of Letters Patent. Patented Sept. 13, 1921.

Application filed November 6, 1919. Serial No. 336,113.

To all whom it may concern:

Be it known that I, EDWARD A. LUZENBERG, a citizen of the United States, residing at San Antonio, in the county of Bexar and State of Texas, have invented certain new and useful Improvements in Stands for Rolled Goods, of which the following is a specification.

The invention relates to means for facilitating the handling of textiles and like goods usually rolled for convenience of storage and manipulation. Duck, canvas, linoleum, carpets and like fabric are generally rolled or bolted when placed upon the market and are unwound from the roll or bolt as required for use. When the rolls are heavy and bulky they cannot be easily handled by one person.

The present invention provides a stand for supporting the roll of fabric in upright position and which admits of the goods being unrolled as required with ease and any surplus amount being rewound so as not to be in the way.

The drawings illustrate a preferred embodiment of the invention. However, it is to be understood that in adapting the same to meet different conditions, various changes may be resorted to without departing from the nature of the invention.

Referring to the accompanying drawings, Figure 1 is a front view of a stand embodying the invention.

Fig. 2 is a horizontal section on the line 2—2 of Fig. 1 looking upwardly as indicated by the arrows.

Fig. 3 is a horizontal section on the line 3—3 of Fig. 1.

Fig. 4 is a sectional detail on the line 4—4 of Fig. 3, the parts being illustrated on an enlarged scale.

Fig. 5 is a horizontal section on the line 5—5 of Fig. 1, the parts of which are likewise illustrated on an enlarged scale.

Fig. 6 is a sectional detail on the line 6—6 of Fig. 3, showing the parts thereof on an enlarged scale.

Corresponding and like parts are referred to in the following description and indicated in the several views of the drawings by like reference characters.

The stand comprises a telescoping frame, and a telescoping shaft whereby it may be

adapted to rolls of goods of different widths. While the stand may be disposed in any relative position it is particularly constructed for use in upright position so as to economize space and enable the goods to be handled with comparative ease and convenience. The main frame comprises a base 1, uprights 2 and cross pieces 3 connecting the uprights at their upper ends. The base 1 has an extension 4 which is adapted to support the extensible shaft. The uprights 2 are channeled or grooved to form ways in which the auxiliary frame is mounted for sliding movement. The auxiliary frame comprises uprights 5, lower connecting pieces 6, upper connecting pieces 7 and a top or cap plate 8 to which the upper ends of the uprights 5 are connected in any substantial way. The auxiliary frame 5 has a telescoping connection with the main frame to admit of adapting the stand to rolls of different lengths. Binding screws 9 threaded into the uprights 2 admit of securing the auxiliary frame in the required adjusted position, an arm 10 is hingedly connected at its inner end to the top or cap plate 8 and is adapted to receive the upper end of the extensible shaft. The arm 10 is hinged so as to swing downward and is supported in horizontal position by means of a brace 11 which is connected at its ends to the arm 10 and part 8. A notch 12 is formed in an edge of the arm 10 and receives the upper portion of the extensible shaft. A latch 13 pivoted at one end to the arm 10 is adapted to extend across the notch 10 and retain the extensible shaft in position.

A block 14 of circular form is secured centrally to the upper side of the base 1 and is provided on its upper side with a metal disk 15 and a ring 16. A pin 17 projects vertically from the block 14 and constitutes an axis to receive the lower end of the roll or bolt of goods when placed in position upon the stand. A plurality of casters 18 is mounted upon the base 1 equidistant from the pin 17 and supports a table 19 which receives the roll or bolt of goods. It is preferred to construct the table 19 of wood in layers and to have the layers arranged so that the grain or one layer crosses the grain of the other. A metal plate 20 is secured to the upper side of the table and

sustains the wear. A metal plate 21 and ring 16' are secured to the under side of the table 19. The metal ring 16' is adapted to revolvably engage the metal ring 16. The table 19 is adapted to rotate about the pin 17 upon the casters 18 and is retained in position by means of the said pin.

The top or cap plate 8 of the auxiliary frame is provided centrally with a spindle 10 22 which corresponds to the pin 17 and is adapted to engage the upper end of the roll or bolt of goods. The spindle 22 is journaled in the part 8 and is provided at its upper end with a crank 23. A head 24 is 15 secured to the spindle 22 and is adapted to engage the upper end of the roll or bolt of goods. A plurality of pins 25 project from the head 24 in parallel relation to one another and to the spindle and are adapted to 20 enter the roll so that the latter may be turned when the spindle 22 is rotated by means of the crank handle 23.

The extension 4 of the base 1 is provided with a block 26 which is centrally apertured 25 to receive the lower end of the extensible shaft. A wear plate 27 is disposed between the block 26 and extension 4 and the lower end of the extensible shaft rests thereon. A metal ring 28 is secured to the top side 30 of the block 26. A rotary table 29 similar in construction to the rotary table 19 is mounted upon the block 26 and is centrally apertured to receive the lower end of the extensible shaft. A metal plate 30 and ring 28' 35 are secured to the lower side of the table 29. The metal ring 28' is adapted to revolvably engage the metal ring 28. The extensible shaft 31 may be of any construction to admit of its lengthening and shortening to 40 adapt itself to the adjustment of the stand according to the length of the roll to be supported thereby. A crank handle 32 is provided at the upper end of the extensible shaft for rotating the same to admit of the 45 goods being wound on the shaft when required. A clip 33 at one side of the extensible shaft engages the upper edge portion of the goods and retains the same in position to cause the winding of the goods on the 50 shaft when the latter is rotated. The lower end of the shaft passes through an opening 34 formed centrally in the table 29 and enters the opening formed in the block 26 thereby retaining the table 29 in position. 55 The upper portion of the shaft may be readily placed in position or disconnected from the arm 10 by reason of the notch 12 and latch 13.

The goods in the form of a roll or bolt is 60 adapted to be supported by the stand by being placed upon the table 19 with the pin 17 extending upwardly into the center of the roll. The frame is adjusted so that the spindle 22 enters the upper end of the roll 65 together with the pins 25. After the frame

has been adjusted to the length of the roll, the telescoping parts or auxiliary frame is made secure by means of the fastenings 9. When it is required to obtain a length of the goods the loose end is grasped and pulled so as to unwind the required amount from the roll. When unwinding the goods from the roll the extensible shaft 31 may serve as a guide. After the desired amount of goods has been obtained and cut from the roll any surplus amount may be readily rewound upon the roll. The length of goods cut from the roll may be rewound by using the shaft 31 as a core and after such goods has been formed into a roll the latter may be detached from the stand by drawing the upper section of the shaft 31 upwardly, and subsequently lifting the roll from the table 29 after which the lower section of the shaft may be withdrawn from the roll and replaced in the stand.

The foregoing description and accompanying drawings have reference to what might be considered to be the approved or preferred form of my invention. I desire 90 it to be understood that I may make such changes in the construction, combination and arrangement of parts, materials, dimensions, et cetera, as may prove expedient and fall within the scope of the invention as 95 claimed hereinafter.

Having thus fully described my invention what I claim as new and desire to secure by Letters Patent, is:—

1. A stand for supporting a roll of goods 100 comprising a base, uprights projecting from the base, other uprights having sliding engagement with the uprights of the base, a cap plate connecting the adjustable uprights, a rotary table mounted upon the said base, a pin 105 projecting from the base and passing centrally through the rotary table, a spindle mounted in said cap plate, a head rotatable with the spindle, and a pin projecting from the head to make positive engagement with 110 the roll.

2. A stand comprising telescoping frames provided with roll engaging means, a rotary table supported laterally of the frames, a telescoping shaft having detachable engagement 115 with the said frame laterally of the roll engaging means and serving to hold the said rotary table in position, and means on said shaft for engaging goods to cause the same to wind about the shaft when rotary movement is imparted thereto.

3. A stand for supporting a roll of goods comprising telescoping frames relatively adjustable longitudinally of each other to receive rolls of different length, means associated with the said frames for engaging and supporting a roll of goods within the frames, a roll rewind-shaft supported outwardly from the said frames on one side thereof and in parallel longitudinal relation 130

thereto, whereby it serves as a guide in unwinding goods from the roll of the engaging and supporting means, crank means for rotating the rewind-shaft, and clip means carried by said shaft for connecting the roll of goods thereto whereby the latter may be rewound thereon when the shaft is rotated.

In testimony whereof I affix my signature in presence of two witnesses.

EDWARD A. LUZENBERG.
